WINDOW CARTON WITH CUSHIONING STRUCTURE

Raymond A. Cote, Philadelphia, Pa., assignor to Container Corporation of America, Chicago, Ill., a corporation of Delaware

Application June 9, 1955, Serial No. 514,358

3 Claims. (Cl. 229—27)

The present invention relates to collapsible folding cartons and more particularly to a form of folding carton which has combined therewith cushioning structure to give added protection to contents such as bottles and other fragile articles.

An object of the invention is to provide a simple, effective and easily manufactured, collapsible carton which has cushioning structure combined therewith and which can readily be produced on conventional folding and gluing machinery.

Another object of the invention is to provide a folding carton with cushioning structure combined with display or window openings and wherein portions removed from a wall to provide a display window are preserved and utilized to form internal cushioning means.

A further object of the invention is to provide a neat and attractive, yet economical, display carton which can be manufactured in a flat, collapsed, tubular form, and which provides display windows in two opposite side walls with cushioning means disposed at each side of the windows, interiorly of the carton.

A still further object of the invention is to provide a collapsible, tubular carton formed from a single blank of paperboard, the carton having window openings in two opposed, relatively wide side walls with internally positioned cushion panels at the sides of the windows formed in part from portions cut from one of the panels to form the window therein, and in part from an extension at one end of the paperboard blank whereby, when paperboard is employed having a relatively costly lined surface on one side combined with less costly materials for the body of the paperboard, the cushion panels will be so formed that the more attractive surface will show through the window openings and the total effect will be a display carton in which a highly pleasing appearance will be obtained from relatively inexpensive paperboard.

Additional objects will become apparent as the description proceeds.

In the drawings:

Fig. 1 is a perspective view of a carton made in accordance with the present invention showing it in set up condition, and showing certain parts partly broken away;

Fig. 2 is a perspective view on a reduced scale, illustrating the carton as it appears when holding a rectangular shaped bottle such as may be used for cosmetics and other liquids;

Fig. 3 is a plan view of a blank from which the carton may be constructed;

Fig. 4 is a perspective view illustrating the carton in a flat, collapsed form; and

Fig. 5 is a sectional plan view taken along line 5—5 of Fig. 1.

The carton embodying the present invention comprises essentially a tubular construction having suitable closure flaps top and bottom and having two opposite major wall panels joined to narrower wall panels at the edges

2

of the carton, the major panels having relatively large display openings to give a frame effect, and the material which is cut from one of the openings being left attached along one of the edges and arranged as a vertically disposed cushioning member in the process of constructing the carton. A second vertical cushioning member is conveniently provided by forming an extension on the end of the blank, the result being that a carton is provided that not only gives protection to a bottle of liquid or other fragile article contained therein during handling and shipment, but also produces a pleasing appearance due to the frame-like effect that is given the carton by the formation of the cushioning elements at the sides of the windows.

15 Referring more particularly to the drawings, the carton is preferably formed from a single blank of foldable sheet material, such as folding paperboard, cut and creased to provide a side wall 10, an edge wall 11, hinged thereto along crease line 12, a side wall 13 hinged to the edge wall 11 along crease line 14, a second edge wall 15 hinged to the second side wall 13 along the crease line 16, and a securing flap 17 along the opposite edge of the edge wall 15 and hinged thereto along crease line 18. The carton, as thus far described, may be secured together in collapsed tubular form by adhesively securing the attaching flap 17 to the edge portion of the side wall 10 at the remote end of the carton blank.

The carton is preferably made in the so-called reverse tuck style with a closure 21, which may be termed the top closure, carried on side wall 10 and defined therefrom by crease line 22. The closure 21 has a tuck flap 23 defined therefrom by crease line 24. Edge wall flaps 25 and 26 are carried at the top of the edge walls 11 and 15 and are hinged thereon along the respective crease lines 27 and 28. A bottom closure 31 is hinged to side wall 13 along crease line 32 and carries a tuck flap 33 hinged thereto along crease line 34. Flaps 35 and 36 are carried on the lower ends of the edge walls 11 and 15 and are defined therefrom by crease lines 57 and 58.

40 Display openings are preferably provided in both side wall panels, and occupy a major portion of the width of the panels. In the present invention display opening 41 cut in panel 10 has the material of the cut portion entirely removed from the panel. In the side wall panel

45 13 a cut is likewise formed to provide an opening 42 which extends across major portion of the width of the wall, but in this instance the material of the cut portion is only partly removed, there being left attached to one edge of the opening 42 a panel 43 hinged along crease line 44 and carrying at its outer edge a securing flap 45 hinged to panel 43 along a crease line 46. The width of the securing flap 45 is preferably such that when the free edge of the flap 45 is in contact with the hinge line between walls 10 and 11, the panel 43 will be in connected relation to the inner face of wall panel 10 substantially along the adjacent vertical edge of the opening. The panel 43, when thus secured to the wall 10 by means of the securing flap 45, serves as a cushion panel and at the same time gives a frame-like effect when the panel 43 is viewed through the display openings.

50 In order to provide a cushion or member on the opposite side of the display opening a panel 49 is formed on the outer edge of securing flap 17 and is hinged thereto along crease line 50. The panel 49 carries a securing flap 51 on its outer edge hinged thereto along crease line 52. The panel 49 is brought into cushion-forming relation with the carton by bringing it to a position substantially parallel with wall 15 and securing the flap 51 flat against the inside face of wall 13 between the vertical edge of the display opening and the hinge line 16, and preferably with the edge of the securing flap 51 resting

55

60

70

against the hinge 16. By forming the securing flap 51 of a width equal to the inside dimensions of the wall 13 between the crease line 16 and the adjacent edge of the display opening, the panel 49 will assume, in the set up condition of the box, a position substantially flush with the vertical edge of the opening 42 and thus will serve not only as a cushion on the interior of the carton, but will also give a neat, frame-like appearance to the interior of the carton when viewed through the display openings, similar to the cushioning panel 43 previously described.

The form of carton constructed from a single blank of paperboard is well suited to production on high speed folding and gluing mechanism. As illustrated in Fig. 4, showing the blank from which the carton is preferably formed, adhesive may be applied mechanically to three areas, namely, the area 55 at the edge of panel 13 adjacent to the crease line 16, and the areas 56 and 57 at the vertical edges of the window 41 on panel 10. The glued area 55 receives contact of the securing flap 51; area 56 receives contact of the securing flap 45; and area 57 receives the contact of the securing flap 17. After the adhesive has been applied the parts are folded over in a manner which is well known so that the proper connecting flaps are joined with the areas to which they are to be adhered. The carton is thus formed in flattened or collapsed tubular condition ready to be shipped to the user.

The carton as so constructed has the advantage that it may be made up of relatively inexpensive paperboard of the type in which only one surface is provided with a clear white or colored liner giving good printability and having an attractive appearance while the remainder of the sheet may be of less expensive stock. Due to the fact that the panels 43 and 49 are folded through angles of 180° from their original positions in the blank their better surface will be disposed toward the inside of the carton and as these surfaces are viewed through the window openings very little of the reverse side of the paperboard is seen when the carton is viewed in empty condition and this becomes even less when the carton receives desired contents such as a bottle of perfume, liquid cosmetics or other liquid.

It is thus apparent that there is provided a carton that not only is well adapted to display contents contained therein but at the same time will provide a substantial measure of protection for fragile articles. Packing of articles contained in such cartons in multiple groups such as in shipping containers can be simplified as it is only necessary in many cases to place flat protecting pads between the adjacent wide faces of the individual packages and no protecting members need be placed adjacent the edge portions of the packages.

While the present description sets forth a preferred embodiment of the invention, numerous changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A collapsible paperboard display carton having opposed, relatively wide side walls of equal width and opposed, relatively narrow edge walls of equal width arranged in tubular form, one edge wall having a securing flap for securing such edge wall to the edge portion of a side wall, the securing flap having an extension panel thereon arranged to be secured interiorly of the carton and in substantial parallelism with the edge wall on which it is carried whereby to form a cushion member, and cuts in

each of the side walls forming window openings having edges approximately aligned with the plane of the cushion panel, the stock cut from one side wall to form its display window being left hinged to an edge thereof parallel with the tubular axis of the carton, to provide a second cushion panel of a width commensurate with the edge wall width, and means for securing the second cushion panel in parallelism with the edge wall opposite to that carrying the first mentioned cushion panel.

2. A one piece collapsible display carton comprising a first side wall and a second side wall disposed in spaced substantially parallel relation, a first edge wall extending between said side walls and integrally attached thereto along fold lines, a second edge wall extending between said side walls and integrally attached at one edge along a fold line to said second side wall, said first side wall having therein an opening of substantial area the sides of which are substantially parallel with said edge walls and said second side wall having an opening therein similar to and aligned with said opening in said first side wall, a first securing flap integrally attached at its outer edge along a fold line to the other edge of said second edge wall and secured to the adjacent edge portion of said first side wall with its inner edge substantially in register with the adjacent side of said opening, a cushion panel integrally attached at one edge along a fold line to the inner edge of said flap and extending therefrom to said second side wall in substantial parallelism with said second edge wall, a second securing flap integrally attached along a fold line to the other edge of said cushion panel and extending therefrom toward said second edge wall, said second securing flap seating on and being secured to the inner face of said second side wall, a second cushion panel cut from said opening in said second side wall integrally attached at one edge thereto along a fold line at the side of said opening adjacent said first edge wall and extending therefrom to said first side wall in substantial parallelism with said first edge wall, and a securing flap integrally attached at its inner edge along a fold line to the other edge of said second cushion panel and extending therefrom toward said first edge wall, said last mentioned securing flap seating on and being secured to the inner face of said first side wall.

3. A collapsible paperboard display carton having opposed, relatively wide side walls of equal width and opposed, relatively narrow edge walls of equal width arranged in tubular form, one edge wall having a securing flap for securing such edge wall to the edge portion of a side wall, the securing flap having an extension panel thereon arranged to be secured interiorly of the carton and in substantial parallelism with the edge wall on which it is carried whereby to form a cushion member, and a cut in one side wall forming a window opening having edges approximately aligned with the plane of the cushion panel, the stock cut from said one side wall to form its display window being left hinged to an edge thereof parallel with the tubular axis of the carton, to provide a second cushion panel of a width commensurate with the edge wall width, and means for securing the second cushion panel in parallelism with the edge wall opposite to that carrying the first mentioned cushion panel.
